Primary Examiner — Cynthia Ramirez*Assistant Examiner* — Michael A Maharajh(74) *Attorney, Agent, or Firm* — 3M Innovative Properties Company; Jonathan V. Sry(57) **CLAIM**

The ornamental design for a rolling cart, as shown and described.

DESCRIPTION

FIG. 1 is a perspective view of a rolling cart showing our new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the figures are for the purpose of illustrating portions of the rolling cart, which form no part of the claimed design.
